FIG. 1

FIG. 2

FIG. 3

FIG. 4

FIG. 1 is a top plan view of a casserole or similar article showing my new design.

FIG. 2 is a side elevation thereof.

FIG. 3 is an end elevation thereof.

FIG. 4 is a top plan view of a modification of the design of FIG. 1 wherein the top configuration is oval, and the end elevation is similar to that of FIG. 3 and the side elevation is an elongated version of FIG. 2.

The side and end elevations opposite those shown respectively in FIGS. 2 and 3 are identical thereto. The bottom is substantially plain.

I claim:

The ornamental design for a casserole or similar article, substantially as shown and described.
